METHOD OF WRAPPING

Joel L. Collins, Chicago, Ill., assignor to Industrial Patents Corporation, Chicago, Ill., a corporation of Delaware

Application April 6, 1934, Serial No. 719,323

2 Claims. (Cl. 93—2)

This invention relates to a method of wrapping and more particularly to improvements in labelling meat packages and the like wrapped in transparent wrapping material such as cellulose sheeting for example.

One of the objects of this invention is to provide a method of labelling packages in such manner as to protect the label. Another object of this invention is to provide a method of wrapping packages so that the label is independent of the wrapper and intimately associated with the product so that the removal of the wrapper will not disturb the label.

Other objects will be apparent from this specification.

The invention will be clearly understood by reference to the accompanying drawings in which similar reference characters in the several figures designate similar elements.

20 Figure 1 is an end view of product and labels ready for application.

Figure 2 is an end view of a block of meat placed on a stack of labels.

25 Figure 3 is an end view showing the first step in applying the label.

Figure 4 is an end view showing the third step in applying the label.

Figure 5 is a perspective view showing the fourth step in applying the label.

30 Figure 6 is an end view showing the product with the label applied.

Figure 7 is a top view of the applied label.

Figure 8 is a bottom view of the applied label.

35 Figure 9 is an end view showing the first step in applying the wrapper to the labelled product.

Figure 10 is an end view showing the second step in applying the wrapper to the labelled product.

40 Figure 11 is a top view of the wrapped product.

Figure 12 is a bottom view of the wrapped product.

In carrying out the present invention, product 1 in the form of rectangular blocks, for example, is stacked on a bench or table top 2. A stack of labels 3 is inverted adjacent the stack

of product. One block of the product is placed on top of the stack of labels as shown in Figure 2. The top label of the stack is folded up as shown in Figures 3 and 4, a protecting strip 4 of any desired material having been placed on top of 5 the product.

A solvent for the label material to integrally weld it to itself, or an adhesive is applied to the portion 5 of the label band as by means of felt pad 6. Portion 7 of the label band 3 is then 10 pressed upon portion 5 to secure a bond, and the labelled product appears as in Figures 6, 7 and 8.

The labelled product is then placed on a stack of wrappers 8 and wrapped as may be noted in Figures 9, 10, 11 and 12, the ends being secured as 15 by twisting at 9 and 10. The wrapper 8 is preferably of such transparent material as transparent cellulose sheeting, cellulose acetate or the like. A monogram, trade-mark, advertising matter or other legend as 11 on the label band 3, 20 will then be plainly visible through the wrapper and will be protected thereby.

The bonding of the label band to itself assures the desired permanence and provides a means for hygienically gripping the product for slicing 25 after the wrapper 8 has been removed.

It will be understood that the materials and procedure heretofore described may be altered without departing from the spirit of the invention as described in the claims:

I claim:

1. The method of wrapping a unitary block of meat which comprises placing a protective strip upon one face of the product, folding a label band around the block, tightly securing the ends of the 35 band together over said protective strip and subsequently encasing in a transparent wrapper.

2. The method of wrapping a unitary block of meat which comprises placing a protective strip upon one face of the product, folding a label band of cellulose material about the block with the ends overlapping over said protective strip, securing the ends together to form an integral band secured about the block and then wrapping the banded block in a transparent cellulose sheet. 45

JOEL L. COLLINS.
